UNITED STATES PATENT OFFICE.

ELIZABETH A. TICHLER, OF PATERSON, NEW JERSEY.

DESIGN FOR A TOY ANIMAL.

Application filed November 15, 1922. Serial No. 4,299. Term of patent 7 years.

To all whom it may concern:

Be it known that I, ELIZABETH A. TICHLER, a citizen of the United States, and a resident of Paterson, in the county of Passaic and State of New Jersey, have invented a new, original, and ornamental Design for a Toy Animal, of which the following is a specification, reference being had to the accompanying drawings, in which—

Fig. 2 is a side view thereof.

Fig. 3 is a front view of the same.

I claim:

The ornamental design for a toy animal, as shown.

ELIZABETH A. TICHLER.
